(57) **CLAIM**

The ornamental design for a drumstick as shown and described.

DESCRIPTION

FIG. 1 is perspective view of a drumstick according to the present invention;

FIG. 2 is another perspective view of the drumstick;

FIG. 3 is a front elevation view of the drumstick, the rear and top and bottom views being identical to or mirror images;

FIG. 4 is an enlarged left end view of the drumstick;

FIG. 5 is an enlarged right end view of the drumstick;

FIG. 6 is perspective view of a drumstick according to an alternative embodiment of the invention;

FIG. 7 is another perspective view of the drumstick of FIG. 6;

FIG. 8 is a front elevation view of the drumstick of FIG. 6, the rear and top and bottom views being identical to or mirror images;

FIG. 9 is an enlarged left end view of the drumstick of FIG. 6; and,

FIG. 10 is an enlarged right end view of the drumstick of FIG. 6.

The broken lines illustrate portions of the drumstick that form no part of the claimed design.
